ATTORNEY

UNITED STATES PATENT OFFICE.

THOMAS V. HANDLOSER, OF NEW YORK, N. Y.

DESIGN FOR A FOOT-REST FOR BICYCLE-PEDALS.

SPECIFICATION forming part of Design No. 25,487, dated May 12, 1896.

Application filed September 18, 1895. Serial No. 562,899. Term of patent 14 years.

To all whom it may concern:

Be it known that I, THOMAS V. HANDLOSER, a citizen of the United States of America, residing at New York, in the county and State of New York, have invented and produced a new and original Design for Velocipede-Pedals, of which the following is a specification, reference being had to the accompanying drawing, showing a perspective view thereof.

The leading or characteristic feature of my design consists in a yoke-shaped foot-rest for velocipede-pedals, having parallel limbs and a curved connecting portion or bow, the edges of the limbs being scalloped or corrugated.

As shown in the accompanying drawing, the foot-rest is formed substantially in the

shape of a yoke with parallel or nearly parallel limbs *a* and a curved connecting portion or bow *b*. The edges of the limbs *a* are scalloped or corrugated, as at *c*, and are thereby distinguished from the usual toothed or serrated edges. The connecting portion or bow *b* may be provided with a diamond-shaped opening *d*. 25

What I claim is—

The design for a foot-rest for velocipede-pedals, substantially as described and shown.

In testimony whereof I affix my signature in the presence of two witnesses.

THOMAS V. HANDLOSER.
